UNITED STATES PATENT OFFICE.

JAMES C. HUGHEN, OF WINNFIELD, LOUISIANA.

BARBER-CLOTH PIN.

Application filed January 31, 1923. Serial No. 616,153.

To all whom it may concern:

Be it known that I, JAMES C. HUGHEN, a citizen of the United States, residing at Winnfield, in the parish of Winn and State of Louisiana, have invented certain new and useful Improvements in Barber-Cloth Pins, of which the following is a specification.

The present invention relates to a barber cloth pin and has for its principal object to provide a device of this nature which may be engaged with a barber cloth to remain thereon as desired and including means for holding the barber cloth around the neck of a person in the barber chair.

Another object of the invention is to provide a pin of this nature which includes means for securely holding the pin to the barber cloth and means for grasping the cloth so as to hold it about the neck of the wearer both of said means being disposed exteriorly of the cloth that is the pointed ends thereof so as to eliminate any danger of injuring the wearer when the cloth is being placed upon him.

Another very important object of the invention is to provide a pin of this nature which is formed from a single strand of resilient wire.

A still further important object is to provide a pin of this nature which is simple and efficient in construction, reliable in operation, inexpensive to manufacture, durable, attractive in appearance, and well adapted to the purpose for which it is designed.

With the above and numerous other objects in view, as will appear as the description progresses, the invention resides in novel construction, and the combination and arrangement of parts as will be hereinafter more fully described and claimed.

In the drawing:

Figure 1 is a fragmentary elevation of a barber cloth showing my pin attached to the collar thereon,

Figure 2 is a fragmentary view of one corner of the barber cloth showing the pin attached thereto,

Figure 3 is an edge elevation of the pin showing the same engaged with the barber cloth, and

Figure 4 is a detailed construction of the pin.

Referring to the drawing in detail it will be seen that 1 designates the ordinary barber

cloth which is usually provided with a collar band 2 which is adapted to be disposed tightly about the neck of a person having a hair cut so as to prevent severed pieces of hair from falling or working their way into his or her clothing. My pin is adapted to be attached to one end of this barber cloth. This pin is formed from a single strand of resilient wire having its ends pointed as indicated at 3 and 4. The main pin 5 is provided with the point 3 and is bent at its other end so as to form a convolution 6 and then extends to form one of the side strands 7 of the body of the pin. The other end of this side strand 7 is bent inwardly providing an extension 8 which forms a U-shaped engaging member 9 which engages the end of the main pin member 5 holding it in locked position against displacement when the main pin is engaged with the cloth as is indicated to advantage in the first three figures. An extension 8' similar to the extension 8 is formed on the other side of the U-shaped engaging member 9 and is attached to the other side strand 7'. The other end of this side strand 7' terminates in a curved extension 11 which in turn terminates with a hooked extension 12 having the point 4 which is adapted to engage the other end of the collar 2 as is indicated to advantage in Fig. 3 when the cloth is disposed about the wearer. It is to be noted that when the main pin member 5 is in a locked position as indicated in all figures of the drawing the points 3 and 4 are on the same side of the plane formed by the side strands 7 and 7', that is, on the side opposite to the flesh of the wearer.

Having thus described my invention, what I claim as new is:

1. A pin of the class described formed from a single strand of resilient wire having its ends pointed, said strand of wire being curved so as to provide a main pin member having one of the pointed ends, said main pin member terminating at its opposite end in a convolution and then extending to form a side strand, a U-shaped engaging member for the main pin mounted on the side strand, a second side strand formed on said U-shaped engaging member and extending substantially parallel with the first side strand and terminating in a hooked extension passing through the convolution, said hooked extension being provided with the other of said pointed ends.

2. A pin of the class described formed from a single strand of resilient wire having its ends pointed and curved or bent so as to provide a main pin member having 5 one of the points which terminates at its non-pointed end in a convolution and then extends to form a side strand, a U-shaped engaging member for the main pin member is mounted on the side strand and a second 10 side strand is attached to this U-shaped engaging member and extends substantially

parallel with first side strand and terminates in a hooked extension passing through the convolution and terminating in the other point. 15

In testimony whereof I affix my signature in presence of two witnesses.

JAMES C. HUGHEN.
